J. A. NEAL,
LUMBER BUGGY,
APPLICATION FILED JUNE 30, 1919.

1,324,060.

Patented Dec. 9, 1919.

Inventor

Joseph A. Neal

By William C. Dowell
his Attorney

UNITED STATES PATENT OFFICE.

JOSEPH A. NEAL, OF CRICHTON, ALABAMA.

LUMBER-BUGGY.

1,324,060.

Specification of Letters Patent.

Patented Dec. 9, 1919.

Application filed June 30, 1919. Serial No. 307,688.

To all whom it may concern:

Be it known that I, JOSEPH A. NEAL, a citizen of the United States, residing at Crichton, in the county of Mobile and State 5 of Alabama, have invented certain new and useful Improvements in Lumber-Buggies; and I do hereby declare the following to be a full, clear, and exact description of the invention, such as will enable others skilled 10 in the art to which it appertains to make and use the same.

This invention relates to vehicles of the type known in the art as lumber buggies, and has for its object to provide a lumber 15 buggy having pivotally attached thereto invertible supporting legs adapted in inverted position to serve as standards for holding the load intact as the buggy is pushed along the road or drawn from place to place, together with means for securing said legs in 20 a fixed position extending either upwardly above, or downwardly below, the supporting frame for the purposes stated.

The invention will first be hereinafter 25 more particularly described, with reference to the accompanying drawings, which are to be taken as a part of this specification, and then pointed out in the claims at the end of the description.

30 In said drawings:

Figure 1 is a side elevation of a lumber buggy embodying my invention, the supporting legs being indicated in dotted lines and shown in full lines turned up into position to adapt them to serve as standards for holding the load in place on the wheeled frame;

Fig. 2 is a top plan view;

Fig. 3 is an end elevation, and

40 Fig. 4 is a detail view of a wear-plate adapted to fit over or embrace and prevent the supporting leg from splitting and also to strengthen it and at the same time prevent the nut on the pivot bolt from wearing 45 the leg or standard.

Referring to said drawings, in which the same reference letters are used to denote corresponding parts in different views, the letters A, A, denote longitudinal frame bars 50 which are mounted, preferably about midway of their length, upon wheels B, B, and are connected at opposite ends and about midway thereof, by cross-bars A¹, A² and A³, so as to form a substantially rectangular wheeled frame on which the lumber to be transported may be placed. The free ends

of the longitudinal bars A have pivotally attached thereto, by means of rods C, supporting legs D, whereby the frame may be supported in proper position for loading 60 without anything on the surface thereof to interfere with placing the lumber thereon; said legs being adapted to be turned up after loading into the full line position shown in Fig. 1, so as to serve as standards 65 for holding the load in place as the buggy is being shoved along the road or drawn to the desired place for unloading. The supporting legs D, are each provided with a series of holes d, adapted to register with 70 holes through the frame bars A, in either the raised or lowered positions of the legs, to receive a fastening bolt E, either above or below the pivot bolt, by which the leg may be secured in a fixed position projecting 75 either upwardly or downwardly as desired to serve as a standard or supporting leg. The pivot bolts or rods C, are preferably inserted through holes in wear-plates F, which are formed or provided with end-flanges f 80 adapting them to fit over or embrace the leg or standard so as to strengthen and prevent it from splitting under undue strain and also to prevent the head of the pivot bolt or rod and the nut thereon from wearing the 85 leg or legs.

The utility and advantages of my improvement will be readily understood from the foregoing description in connection with the accompanying drawings. Instead of the 90 trouble and annoyance incident to the use of props or other devices for supporting the ends of the frame while the buggy is being loaded, and which are easily misplaced, the supporting legs are kept on the machine 95 frame, ready to be turned down into position to serve as supports for the frame ends when needed, in which position they will not interfere with the loading of the buggy and may be easily turned up so as not to 100 drag along the floor or ground and interfere with the movement of the buggy from place to place for unloading.

Having thus described my invention, what I claim as new and desire to secure by 105 Letters Patent of the United States, is:—

1. A lumber buggy comprising a frame mounted on wheels arranged about midway of its length, said frame being provided at its free ends with pivotally attached depending supporting legs, said legs being adapted 110 to be turned up into position to serve as

standards for sustaining the load intact, and means for holding said legs in a fixed position, either raised or depending from said frame.

6 2. A lumber buggy comprising a frame mounted on wheels arranged about midway of its length, said frame being provided at each end with a pair of pivotally attached depending supporting legs, said legs being
10 adapted to be turned up into position to serve as standards for sustaining the load in place, and each having a series of holes in its pivoted end registering with holes in the supporting frame adapted to receive a
15 fastening bolt either above or below the pivot of the leg for sustaining the latter in either raised or lowered position.

3. In combination, a supporting frame mounted on wheels arranged about midway
20 of its length, a pair of supporting legs piv-

otally attached to said frame at each end thereof and provided with holes above and below the pivot bolt registering with holes in said frame, the registering holes either above or below said pivot being adapted to receive a bolt for securing said legs in a fixed position, either raised or lowered, so as to serve either as standards or supporting legs, and a wear-plate through which the pivot bolt passes, said plate having end-flanges fitting over the standard so as to strengthen it and prevent it from splitting and also prevent the head of the bolt or nut from wearing the standard.

In testimony whereof I affix my signature 35
in the presence of two witnesses.

JOSEPH A. NEAL.

Witnesses:
